(57) CLAIM

The ornamental design for a glass holder, as shown and described.

DESCRIPTION

FIG. 1 is a front elevational view of a glass holder, such as a hands-free wine glass holder, showing my new design;

FIG. 2 is a right elevational view thereof;

FIG. 3 is a top plan view thereof;

FIG. 4 is a bottom plan view thereof; and,

FIG. 5 is a right front perspective view thereof.

The portions shown in broken lines are for illustrative purposes only and form no part of the claimed design.
